Patented Dec. 17, 1918.

UNITED STATES PATENT OFFICE.

OSCAR LEONARD BAXTER, OF COLUMBUS, OHIO, ASSIGNOR TO THE SOLAR METAL PRODUCTS COMPANY, OF COLUMBUS, OHIO, A CORPORATION OF NEW YORK.

METAL FRAME CONSTRUCTION.

1,287,615.

Specification of Letters Patent. Patented Dec. 17, 1918.

Application filed February 26, 1917. Serial No. 150,925.

To all whom it may concern:

Be it known that I, OSCAR LEONARD BAXTER, a citizen of the United States, residing at Columbus, in the county of Franklin and State of Ohio, have invented certain new and useful Improvements in Metal Frame Constructions, of which the following is a specification.

This invention relates to metal frame construction for interior building finish such as windows, doors and the like. Specifically, the invention has relation to the transom structure used above doors and windows or wherever it may be desired, the arrangement being such that the transom is used for light only and is, therefore, permanently held in its applied position.

The main object, therefore, of this invention, resides in a novel type of structure whereby the transom may be permanently applied in such position. In carrying forth this arrangement, I have also aimed to so construct and arrange the structure that all attaching parts are normally hidden from view, so as not to mar the appearance of the frame structure or transom itself in any manner. Also, in carrying forth this idea, I have endeavored to simplify the structure as much as is possible to correspondingly reduce its cost of production.

The preferred embodiment of my invention is shown in the accompanying sheet of drawings, in which similar characters of reference designate corresponding parts, and in which:

Figure 1 is an enlarged fragmentary sectional perspective taken through the transom portion of a door or window, and,

Fig. 2 is a fragmentary side view of the structure shown in Fig. 1.

In the drawings, there is shown a main frame piece or jamb 1, which is secured in position within the desired wall opening in any preferred manner. A trim structure 2 is also secured in position so that a neat appearance is had. Between the two vertically extending members of the jamb or main framework, there is located a transom rail 3 which, as shown in Fig. 2, is secured in position by means of the bolts 4. These bolts pass through the upper and lower faces of the transom rail and also through the outstanding legs of channel clips 5 which latter are spot welded or otherwise secured to the inside faces of the upper portion of

the jamb, as shown. The inside face of the upper cross piece of the jamb 1 is also provided with a clip structure in the form of a transverse angle shown at 6, which angle is spaced slightly from the door stop bead 7, 60 as is shown. The transom itself comprises a metal frame section 8 whose top face or edge of the upper portion of which is formed and braced by means of the channel 9. This channel is arranged with its legs extending 65 upwardly so that one side of the frame piece 8 may be moved into position in the rear of the angle clip 6 and between this clip and the door bead 7 so that the transom frame, in this manner, is locked against outward 70 or lateral movement, although its removal is permitted by an inclined movement downwardly. The inside of the transom rail is also provided with a reinforcing bar 10 and it is through the top and bottom surfaces 11 75 and 12 between which this reinforcing bar is located, that the screws 13 pass to enter the bottom face 14 of the bottom cross piece of the transom frame 8. The reinforcing bar 10 is preferably adapted to accommodate 80 these screws and the bottom face piece 14 provided with a series of apertures. Additionally, the lower portion of the frame 8 is inclined slightly as is shown at 15 so that it may be readily moved into position after 85 being operatively engaged by the angle clip 6. The screws 13 are then screwed into the reinforcing bar 10 and into the apertures in the bottom face 14 of the transom frame.

In this manner, this transom frame is 90 securely locked in position against removal in any manner and when the door or window is in closed position, these screws are also hidden from view. In this manner, the appearance of the structure is in no wise 95 marred and at the same time gives a very pleasing appearance. A further advantage in this arrangement, is that the transom structure is burglar proof, since the doors or windows are moved into a position preventing access to the screws 13 when they are in closed position.

What I claim, is:

1. The combination with a jamb and transom rail, of a transom frame, a channel 105 shaped top piece for said frame arranged with its legs projecting upwardly, a clip structure carried by the top piece of the jamb with which said channel shaped top piece interlocks to hold said frame against 110

outward movement but removable therefrom downwardly, and a set of screws passing through said rail from its under side into said frame to firmly lock the latter in position.

2. The combination with a jamb and a transom rail, said jamb being provided with a transverse cross bead, of a transom frame, the upper portion of which rests against said bead, a channel-shaped top piece for said frame arranged with its legs projecting upwardly, a clip structure carried by the top piece of said jamb and spaced a distance from said bead to permit the insertion of one of the legs of said channel to hold said frame against outward movement, and a set of screws passing vertically through said rail from its underside through its top side and into said frame.
- 20 3. The combination with a jamb and a hollow transom rail, of a clip mounted at the side of said jamb to fit within the end of said rail, a screw passing vertically through the end of said rail through its top 25 and bottom sides and through said clip,

and a transom held in position between said jamb and rail.

4. In a metal frame construction the combination with a jamb carrying a stop bead at its top and spanned by a transom rail, of a clip lying in parallelism with said bead and in spaced relation thereto a transom frame of sheet metal comprising a substantially rectangular shell the upper edge of which is formed of a channel member substantially of U shape with its legs disposed upwardly, one of said legs and a part of one of the sides of the said frame fitting between the stop bead and the clip, and fastening members removable from the underside of the transom rail which traverse the transom rail and enter the under edge of the transom frame.

In testimony whereof I affix my signature in presence of two witnesses.

OSCAR LEONARD BAXTER.
